DESIGN FOR A KNIFE

Pierre H. Boucheron, Riverside, Conn., assignor to Remington Arms Company, Inc., a corporation of Delaware

Application November 27, 1936, Serial No. 66,168

Term of patent 14 years

To all whom it may concern:

Be it known that I, Pierre H. Boucheron, a citizen of the United States, residing at Riverside, in the county of Fairfield, State of Connecticut, have invented a new, original and ornamental Design for a Knife, of which the following is a specification, reference being had to the accompanying drawing, forming part thereof.

In the drawing:

Fig. 1 is a side elevation, and

Fig. 2 is a plan view of a knife, showing my new design.

What is claimed is:

The ornamental design for a knife, as shown.

PIERRE H. BOUCHERON.
